J. P. MILLER

LOCKING DEVICE FOR MINE CARS

Filed Jan. 26, 1920

Fig. 1.

UNITED STATES PATENT OFFICE.

JOHN P. MILLER, OF DURYEA, PENNSYLVANIA, ASSIGNOR OF ONE-HALF TO HERBERT S. WOODWARD, OF CARBONDALE, PENNSYLVANIA.

LOCKING DEVICE FOR MINE CARS.

Application filed January 26, 1920. Serial No. 353,940.

To all whom it may concern:

Be it known that I, JOHN P. MILLER, a citizen of the United States, and a resident of Duryea, county of Luzerne, State of Pennsylvania, have invented certain new and useful Improvements in Locking Devices for Mine Cars, of which the following is a specification, reference being had to accompanying drawing.

- 10 The invention relates to railway cars adapted for use in conveying materials, such as coal, ores, and the like, in and from mines, and has reference more particularly to a new and improved door and locking means 15 therefor whereby the same may be operated to positively retain the contents of the car therein without any danger of a premature opening of the door and dumping of the contents irrespective of the rough handling 20 of the car and whereby the same also may be easily operated from either side of the car by an operator or miner for opening the door at the time when it is desired to dump the contents of the car.
- 25 An object of my invention is to provide new and useful means of simple construction for positively and safely retaining the door of the car in locked and closed position until it is manually operated to permit the 30 opening of the door thereof.

Another object is to provide the car door with a locking device at both ends of the door whereby the warping of the door is prevented and to connect said locking devices in such a manner that the operation of either will cause a simultaneous operation of the other.

Another object of my invention is to so construct and arrange the parts of the locking means that the weight thereof will move or urge and constantly maintain the parts into locking and locked position respectively.

Another object is to provide the locking devices with a connecting link adapted to 45 be selectively connected in either of two positions with relation to the locking devices located at both ends of the door whereby the manual operation of one of said locking devices will produce a pull or thrust, in transmitting motion to the other locking device.

A still further object is to provide each locking device with a pivotally mounted

latch and to so form the latch that a relatively small angular movement of the part acted upon for the unlocking operation will 55 produce a relatively greater or larger movement of the part normally in locking engagement with a fixed part of the car.

A still further object is to provide each locking device with a locking plate having 60 an inclined slot the inclination of which cooperates with the latch of the locking device to positively maintain the latch in locked position by the lateral thrust of the load in the car, the tendency to so maintain the latch 65 in locked position increasing with such lateral thrust.

A still further object is to so arrange the door that it will open or swing outwardly under the influence of the lateral thrust or 70 weight of the contents of the car.

Other objects and advantages of my invention will be more fully disclosed in the following specification.

Referring to the drawings, in which the 75 same reference characters designate corresponding parts in the views illustrated,

Fig. 1 is a vertical elevation of an end of a car provided with my invention, and,

Fig. 2 is a fragmentary detail in side view 80 of one of the locking devices.

Referring now more particularly to the drawing the car comprises in general a body of open box type supported upon a chassis which is in turn mounted upon a truck 85 adapted to travel over the rails of a railway.

The body of the car comprises a floor 1, side walls 2 and end doors 3. The side walls of the car may be suitably braced by stakes 4 secured, in any appropriate manner, at 90 their lower ends to the chassis 5 and braced at their upper ends by tie bolts 6. The chassis may comprise longitudinally disposed beams or sills 7, provided with end bumpers 8, mounted in any suitable manner upon the truck 9, the latter being adapted to operate over the rails 10. At the sides of the body of the car and adjacent the top thereof may be provided longitudinal side members 11 mounted in any desired manner upon the 95 sills 7, as is clearly shown in Fig. 1 of the drawing.

The body of the car is constructed with open ends normally closed by doors 3 pref-

erably of wood, the parts of which may be firmly held together by U-shaped straps 12 secured thereto by means of bolts or rivets 13. The door is hingedly mounted in a depending position upon an end tie rod 6 so that the door may swing thereabout pendulously. The end tie rod 6 may be mounted in brackets 14 suitably secured to the top of the side members 11 and may be provided 10 with tubular spacing members 15 interposed between the brackets 14 and the upper or hinge portions 12' of the straps 12 to maintain the door in proper position.

At both ends of the door and near the 15 lower corners thereof are attached locking devices each comprising a Z-shaped bracket 16 suitably secured to the door by means of bolts 17 and with its lower end 18 disposed in spaced relation to the door to include 20 therebetween a pivotally mounted latch 19, the latter being mounted upon a pivot pin 20 passing through a perforation provided in the lower end of the portion 18 and the door 3. The latch 19 is preferably constructed 25 of metal and provided with hubs 21 forming a bearing member for the pivot pin 20 and is provided with an impact projection 22, a locking tongue 23 and a link connecting weighted portion 24, the latter being disposed on the opposite side of the 30 pivot pin 20 from the impact portion and the locking tongue. The portion 24 is so formed as to comprise a larger amount of material than that included in the members 35 22 and 23 so that the portion 24 is of considerably greater weight than the members 22 and 23 whereby the portion 24 is constantly urged downwardly by the force of gravity about the pivot pin 20 for the purpose 40 of moving and maintaining the locking tongue 23 into locking and locked position respectively, as will appear more fully hereinafter.

The portion 24 of each latch 19 is provided 45 with a pair of perforations 25 and 26 whereby a connecting rod 27 may be selectively connected in either of the positions shown in full or dotted and dash lines in Fig. 1 of the drawing. The connecting link may be provided at its ends with bifurcated members 28 spanning the portions 24 and pivotally secured thereto by pins 29 suitably held in place, in either of the perforations 25 or 26, by cotters 30. It will 50 be observed that when the link 27 is connected with the perforation 26 of one of the latches 19 the other end of the link is connected with the perforation 25 of the other latch so that upon operating the latter latch, 55 as for example, that shown to the left of Fig. 1, to move the same into unlocked position, the link 27 will be given a pull to substantially simultaneously operate the other latch 19, as for example, that shown to the 60 right of Fig. 1. Obviously, if it is desired, 65

the latch at the right may be operated and a thrust will be transmitted through the link 27 to the latch shown at the left, although in practice I have observed that the transmission of the force through a pull appears to 70 be more satisfactory than by a thrust and accordingly in the event of operating the latch 19 shown at the right side of Fig. 1 the link 27 may be located in the dot-and-dash line position in order that the force 75 transmitted to the other latch will be a tensile force through the link 27.

At each side of the body of the car is attached a locking plate 31 suitably secured to the side wall 2 of the car by means of 80 bolts 32 and held in spaced relation to the side of the car by an interposed spacer 33, as is clearly shown in Fig. 1. Each locking plate 31 is provided with a slot 34, which is slightly inclined to the vertical, as shown 85 in Fig. 2, and through which the end of the tongue 23 is adapted to project when in locked position. By inclining the slot 34 with its upper end more remote from the door than its lower end, any lateral 90 force tending to move the tongue 23 relative to the plate 31 will cause the tongue to move upwardly in the slot 34, thereby positively maintaining or more firmly urging the parts in locked position and avoiding any possibility of the tongue 23 being worked free from the plate 31 until it is forcibly moved by the operator in the manner hereinafter disclosed. It will be noted by locating the pivot pin 20 with relation 95 to the latch parts so that the tongue 23 will be considerably longer than the impact portion 22, a blow given to the portion 22 with a hammer or similar instrument causing a 100 comparatively small movement of the impact portion 22 will cause a relatively large movement of the locking tongue 23 whereby the same may be rapidly moved through the slot 34 and cleared from the locking plate 31.

In use and operation the doors are swung into vertical position, but if the latches are not properly located to permit the door to completely close, the operator may grasp the connecting rod 27 and move it, to the 115 left as shown in Fig. 1, to clear the locking tongue by the edge of the plates 31. After the door has moved into completely closed position the locking latches 19 may then be permitted to move into locking position by gravity due to the weight of the portions 24 combined with the weight of the link 27 connected thereto and the same will be retained in locked position by reason of the weight of the parts referred to 120 above. The car may then be filled with material such as coal, and the same conveyed to its destination. The lateral thrust of the 125 contents of the car will constantly urge the opening of the door and when it is desired, 130

to dump the contents of the car the operator may operate the locking means, to unlock the same for the purpose of permitting the door to open, by giving a comparatively 5 light blow with a hammer or the like upon the impact portion 22 of the latch 19. This results in causing the impact portion to move downwardly about the pivot pin 20 and to also cause a comparatively long 10 sweep of the locking tongue 23 through the slot 34 of the locking plate 31 to disengage the same therefrom. If desired, however, the latch may be forcibly moved, with the same result, by means of a lever of any 15 suitable form, such as a crow-bar. In this case the end of the lever may be fulcrumed against the under surface 35 of the Z-bar 18 and with its power point of contact bearing against the top of the impact portion 20 22 of the latch. With the parts in position as shown in Fig. 1, the impact or force delivered or applied to the latch shown at the left will be transmitted through the link 27, in the form of a tensile stress, to the latch 25 shown at the right. In this manner the disengaging operation between the tongues 23 and the plates 31 occurs simultaneously at both ends of the door and the door is then permitted to open to discharge the contents 30 of the car.

It is the usual practice to run the car upon an incline tipple and to open the door at the lower end thereof for the purpose of discharging the contents of the car, the inclination of the car aiding in the discharge 35 of the contents therefrom.

While I have herein illustrated and described one embodiment of my invention with considerable particularity, I do not however, desire or intend to limit myself 40 specifically to the particular details disclosed, as considerable changes and modifications may be made in the details and arrangements of the means shown and employed without departing from the spirit 45 of the invention and the scope of the appended claims.

Having thus described my invention, what I claim as new and desire to protect by 50 Letters Patent of the United States is:

1. In a locking device for mine car doors, the combination of slotted locking plates fixed to the sides of said mine car adjacent the ends thereof, a pair of locking latches 55 pivotally mounted on said door adjacent said plates and operative in planes transverse to said plates, said latches comprising means adapted to engage in the slots of said plates for normally maintaining said door 60 in closed position, a link connecting said latches, said link having one end pivoted to one latch on one side of a plane passing through the axes of the pivots of said latches and its other end pivoted to the other latch on 65 the opposite side of said plane, whereby an

operating movement of either latch will be imparted by said link to simultaneously similarly operate the other of said latches.

2. In a locking device for mine car doors, the combination of slotted locking plates 70 fixed to the sides of said mine car adjacent the ends thereof, a pair of locking latches pivotally mounted on said door at the ends thereof and adjacent said plates, said latches comprising means adapted to engage in the 75 slots of said plates for normally maintaining said door in closed position, each of said latches being provided with a pair of vertically spaced perforations, a link connecting said latches, one end of said link being connectible with one of said latches through the lower perforation thereof and the other end of said link being connectible with the other of said latches through the upper perforation thereof whereby an operating movement 80 of either latch will be imparted by said link to simultaneously operate the other of said latches.

3. In a locking device for mine car doors provided with a slotted locking plate fixed 90 to the side of said mine car adjacent the end thereof, the combination of a pivotally mounted locking latch on said door adjacent said locking plate, said latch comprising a relatively long locking tongue adapted to enter the slot of said plate, a relatively short portion movable under impact or pressure whereby a small movement thereof will cause a relatively large movement of the end 95 of said tongue to disengage the same from said plate and a weighted portion whereby said latch including the tongue is normally moved and held into locking position by the weight thereof when the car door is moved 100 into closed position.

4. In a mine car comprising a car body, chassis truck and an end door therefor, the combination of a locking means for said door comprising locking plates provided 110 with slots secured to said car body at the sides thereof, angularly movable latches pivotally mounted upon said door adjacent said locking plates, each of said latches including a relatively long locking tongue adapted to move into and out of the slots in said locking plates, a relatively short impact portion and weighted portion located on the opposite side of the pivotal mounting of said latch from said tongue and said impact portion whereby the weight of said weighted 115 portion maintains and constantly urges said locking tongues into the slots of said plates and a connecting link between said latches whereby the operation of one latch will cause the simultaneous operation of the other 120 latch.

5. In a mine car comprising a car body, chassis truck and an end door therefor, the combination of a locking means for said door comprising locking plates provided with 125

4
inclined slots secured to said car body at the sides thereof, angularly movable latches pivotally mounted upon said door adjacent said locking plates, each of said latches including a locking tongue adapted to move into and out of the slots in said locking plates and an impact portion, the inclination of said slots operating to maintain and con-

stantly urge said locking tongues into locked position and a connecting link between said latches whereby the operation of one latch will cause the simultaneous operation of the other latch. 10

In witness whereof, I have hereunto set my hand this twentieth day of January, 1920.

JOHN P. MILLER.
